UNITED STATES PATENT OFFICE.

EDWARD POOLE, OF HALIFAX, ENGLAND, ASSIGNOR TO JOSEPH WILD & CO., OF NEW YORK, N. Y.

DESIGN FOR A CARPET-PATTERN.

Specification forming part of Design No. 5,799, dated April 16, 1872.

Specification describing a new and original Design for a Carpet, invented by EDWARD POOLE, of Halifax, in the county of York, England.

The accompanying photograph fully illustrates my new design.

This invention relates to a new carpet design, which is principally composed of two large star-shaped figures, of which one contains an octagon, the other a square, in the center, both being ornamented and shaped as shown.

I claim as my invention—

The design for a carpet, as shown.

EDWARD POOLE.
